(57) **CLAIM**

The ornamental design of a combination ear muffs and goggles, as shown and described.

DESCRIPTION

FIG. 1 is a front isometric view of the combination ear muffs and goggles,

FIG. 2 is a front view of the combination ear muffs and goggles,

FIG. 3 is a rear view of the combination ear muffs and goggles,

FIG. 4 is a right-side of the combination ear muffs and goggles,

FIG. 5 is a left-side view of the combination ear muffs and goggles,

FIG. 6 is a top view of the combination ear muffs and goggles; and,

FIG. 7 is a bottom view of the combination ear muffs and goggles.

The portions shown in broken lines are environmental matter and do not form part of the claimed design.

1 Claim, 7 Drawing Sheets
